UNITED STATES PATENT OFFICE.

MONT C. MERKER, OF PHILADELPHIA, PENNSYLVANIA.

DENTAL CHAIR.

SPECIFICATION forming part of Letters Patent No. 605,255, dated June 7, 1898.

Application filed April 23, 1897. Serial No. 633,476. (No model.)

To all whom it may concern:

Be it known that I, MONT C. MERKER, a resident of Philadelphia, in the county of Philadelphia and State of Pennsylvania, have invented certain new and useful Improvements in Dental Chairs; and I do hereby declare the following to be a full, clear, and exact description of the invention, such as will enable others skilled in the art to which it pertains to make and use the same.

The invention relates to dental chairs, and has for its object to increase their efficiency and their ease, smoothness, and certainty of operation and to simplify their construction and cheapen their cost so far as consistent with the first-named objects.

The invention consists in the construction hereinafter described and particularly pointed out.

20 In the accompanying drawings, Figure 1 is a partial central vertical section of the base, pedestal, and seat-elevating mechanism of a chair. Fig. 2 is a horizontal section on line 2 2 of Fig. 1. Fig. 3 is a partial vertical section, showing pump-operating levers. Fig. 4 is a side elevation, on a larger scale, of two of the said levers. Fig. 5 is a section on line 5 5 of Fig. 4. Fig. 6 is a section of a block containing antifriction-balls. Fig. 7 is a section 30 on line 7 7 of Fig. 6. Fig. 8 is a perspective of a lining for the ball-channel. Fig. 9 is a perspective of a head-rest. Fig. 10 is a partial view of the same on an enlarged scale, several parts being shown as split and separated. Fig. 11 is a longitudinal section of the same 35 parts assembled. Fig. 12 is a perspective of a seat-frame with attached foot-rest frame and a supplemental seat and frame. Fig. 13 is a section on line 13 13 of Fig. 2. Fig. 14 is 40 an isometric broken view of levers. Fig. 15 is a section showing a modified arrangement of antifriction-balls. Fig. 16 is an elevation of a pump-operating lever. Fig. 17 is an enlarged detail of a child's foot-rest.

45 Numeral 1 denotes the base, and 2 the pedestal, of a dental chair.

3 indicates an oil-reservoir formed by the flange 3' of the base, and 4 pumps having each the usual inlet-valve 5 and outlet-valve 5'.

50 7 are passages in the casting 13 by which the pumps communicate with tube 8, fixed in the said casting, seated in reservoir bottom or

base. The casting 13 has a seat 13' in the base and is fixed to the pedestal by a screw or screws 13". A screw-plug having in its top a socket to receive loosely the stem of the valve 5' is denoted by 5X. The valve is normally closed by a spring 5". The removable socketed screw-plug normally holds the valve upright and in operative relation to its seat 60 and also provides for its introduction or removal. For these purposes it is situated immediately under the valve and valve-seat and in the bottom of a detachable part, and the plug-opening is of greater diameter than 65 the valve to provide for the introduction of the latter. The socket in the plug is closed to prevent escape of oil.

6 indicates outlets for lowering the chair in usual manner.

9 denotes an extension-tube sliding on tube 8, and 10 and 10' are packings. A tube 11 is connected to a seat-frame 12. Stops adapted to engage each other when the tubes are relatively moved to the end of their paths are 75 denoted by 14.

15 is a movable extension-tube situated between the pedestal and tube 11. This pedestal extension-tube 15 has at its upper and lower ends a wall made sufficiently thick to 80 permit forming therein continuous channels 16 for the reception of antifriction-balls 16'. In some cases a block 17, provided with such channel, can be fixed in the wall of the tube, as shown in Fig. 13. The portion of the bottom of the channels that receives the most wear from the balls has a lining 18 (see Figs. 7 and 8) of chilled steel or of a specially hard alloy or metal to obviate wear, cast-iron or brass being too easily worn. This channel 90 and lining are made concave, as indicated in said figures, to conform transversely to the balls, which are freely movable lengthwise of the continuous channels. The lower balls bear upon a stiff steel rib or plate 19, adjustably supported by the screws 20, passing through threaded openings in the pedestal projections 21 and, if desired, through the projections 22 in the reservoir. These plates and groups of friction-balls may be varied in 95 number as desired.

In Fig. 2 are shown two upper series of balls bearing on plates 19 and a double series bearing on a plate 19' of double width, the

object of this being to prevent independent rotation of the pedestal extension 15. Intermediate the several series of balls described are similar antifriction devices situated in tube 15 and having balls bearing on tube 11. At one point the series of balls is doubled, and the extension-tube 11 also has a flattened portion 11', made sufficiently wide to serve as a bearing for the two rows of balls, as shown, the purpose being to obviate independent horizontal rotation of said tubes 11 and 15.

Instead of employing distinct sets of balls at the top and bottom of the tube 15 a continuous channel may be formed extending 15 nearly the whole length of the tube and holding a single continuous series of balls arranged at its upper end to bear on the tube 15 and at its lower end to bear on a plate 19. Such construction is indicated in Fig. 13.

20 An extension-tube situated between the pedestal and a plunger-tube, each of the latter being provided with antifriction devices, requires that the walls of both the pedestal and the plunger-tube be made thick to provide 25 suitable space and support for said devices. It is characteristic of the present improvement that the channels for the balls are situated entirely in the pedestal extension, which alone need be made thick to provide 30 space for them.

Where the antifriction-balls or equivalent devices are arranged in one set, substantially as shown in Fig. 15, the bottom ones when lowered will descend into the oil-reservoir and be lubricated by the oil therein and will by their movement lengthwise of their containing-channel and by the movement of the pedestal-extension carry oil to lubricate the tube 11 and the plates or tracks connected with the pedestal, against which tube and tracks the antifriction-balls bear at points above the reservoir.

In raising the chair-seat oil is forced into tube 8 and thence into tube 9 and through tube 45 9 into tube 11, supporting the seat-frame. This operation while continued pushes up the telescoping tubes and the seat-frame, the movement of the tubes being limited, respectively, by stops 14 on the tubes and a shoulder 50 14' on the pedestal extension. Thus the ascent of tube 9, if sufficiently continued, will cause the stop at its foot to engage the foot of tube 11 or the stop thereon and the ascent of tube 11 will bring the stop at its foot against the shoulder 14' of the pedestal extension. 55 When tube 9 descends, the stop 14 near its top may engage the stop 14 on the foot of tube 11 and thus prevent their entire separation. The tubes 9 and 11 having been extended as 60 stated, the frame can be raised still further by the exterior part of the stop or flange 14 engaging a shoulder on the interior of the pedestal extension 15, whereupon the tubes and extension may ascend together until the stop 65 at the foot of the pedestal extension engages the top of the pedestal. To reverse the movement and lower the chair, a valve-cock of any

usual or preferred form is opened to permit the oil to escape from the tubes 8, 9, and 11 through outlets 6.

Into a socket in the closed end of tube 11 is screwed an oil-displacing plunger 13^X, terminating in an approximately conical point at or near the level of the bottom of the tube 11 and within the fixed tube 8.

The packings 10 and 10' may be supported in screw-rings 10", screwed into the top of the tubes, an annular space being left between each ring and the oil-displacer. This oil-displacing plunger partially fills the several 80 tubes and occupies the space which would otherwise be filled with oil. The rod or plunger 13^x is elevated simultaneously with tube 11 and its displacing effect in horizontal direction is maintained in said tube and in tube 9 85 at every point of their elevation. Less oil is required to fill them than would otherwise be the case and less time is therefore required to fill or empty them. By this means the quantity of oil in the several tubes is more nearly 90 equalized and the rate of the ascent of the several tubes and the rate of their descent also is equalized. While more power is required to raise the seat at the same speed, owing to the diminution of the transverse 95 area of the oil in the cylinders, and especially in the larger ones, provision is made for this by the compound levers herein described, which levers, though arranged within the small space available for the purpose, enable greater 100 power to be exerted than otherwise practicable.

The pumps are operated by a compound lever comprising the sublevers constructed and operating as described below.

23 denotes a T-lever having a fulcrum at 24 in the swell or lateral enlargement 24' of the pedestal. This enlargement provides space laterally for a pump or pumps between the pedestal and its extension and also for the oscillation of the lever 23. In the absence of this special enlargement of the pedestal neither of these devices could be placed between the pedestal and extension without a very considerable enlargement of the entire pedestal, and the special provision to avoid this is made as indicated in Figs. 2, 3, and 13. The T-lever is situated closely adjacent the relatively wide side 24", approximately tangential to the main part of the wall of the pedestal and connected by a narrow side 24''' to said main cylindrical part. This special form is employed to provide a suitable space for the oscillating T-lever and the piston-rods of the two pumps without unduly enlarging the main part of the pedestal. By this construction the lever can have its fulcrum in the pedestal and move parallel and closely adjacent the side 24", as indicated in Figs. 2 and 13, the pumps being arranged obliquely with respect to the radial lines of the pedestal and in the plane of the lever.

The arms of the **T**-lever are pivoted to pump piston-rods at 25 and 25'. To the foot of the

long arm of the T-lever 23 is pivotally connected at 23' a lever 26, having a fulcrum 27 in the pedestal.

28 denotes a stud or pin to which power is meditately applied by a lever 29. Said latter lever has a fulcrum 30 in the pedestal, and to its fulcrum, outside the pedestal, is fixed the pedal-crank 31. The short arm of the lever 29 has a slot 29', in which is normally held the 10 pin 28.

To operate the pump in raising the chair-seat, the pedal-crank 31 is depressed, with the effect to turn the lever 29 on its fulcrum, which lever by its slotted end applied to the 15 pin 28 rotates the lever 26 about its fulcrum 27 and moves the lever 23 about its fulcrum 24, with the effect to operate the pump-pistons. The pin 28 moves freely in the slot 29' during this operation, as also does the pin 23', 20 held in an oblong slot formed in the foot of the T-lever 23. The described arrangement and combination of levers provides for assembling them in a smaller compass vertically, and the long arm of the main lever 23 can be 25 extended nearer the base and the power very much increased.

A frame for the support of a supplemental seat and foot-rest suitable for children is denoted by 32. This is connected to the chair-seat frame by pivots 33, having suitable bearings 30 in the lugs 34, cast on the frame.

35 denotes an extension of the seat-frame, which may be styled the "foot-rest frame." The frame 32 is similar in form to frame 35, 35 though smaller, and when turned down is situated between the side bars of said frame 35. It may be supported by ledges or lugs 36, situated on the inside of said bars. The child's seat or its frame may when turned 40 down engage with a cross-bar or lug 37 on the main foot-rest frame.

39 denotes an upholstered child's seat. (Shown in operative position in Fig. 12.)

By this construction a child's seat and its 45 frame can be normally held within the main foot-rest frame and serve as a platform and when desired for use can be swung up into a convenient and operative relation to the head-rest, a practical result which has been much 50 desired.

40 denotes a supplementary or child's foot-rest having at 41 pivoted connection with the frame 32. Stops to limit the movement of the foot-rest 40 and retain it in an approximately horizontal position are denoted by 42. When frame 32 is turned down to an inoperative position, the foot-rest 40 is folded up against it by contact with the main foot-rest 55 frame or with ledges or lugs 37 thereon.

60 denotes a detachable arm-rest provided with a screw-threaded stem 61, adapted to be screwed either into the hole 62 in the main seat-frame or into the hole 63 of the child's seat. Such rest can of course be used on 65 either side of the seats.

44 denotes the ball of a universal joint such

as commonly used to support head-rests. Said ball has an arm 43, provided with a ring 45, having an angular opening, as indicated, to fit and move on a similarly-shaped part 46 of a short rod 47. Said rod is screw-threaded at each end and on the lower end is squared to receive a laterally toothed or serrated ring 48, which is held in place by a jam-nut 49. A rotatable hand-wheel having a screw-thread connection with rod 47 is denoted by 50. 60 denotes a washer having a key 62' to enter a slot 61' to prevent friction between the wheel-hub and an arm-ring below. Upon the rod between this ring 48 and the wheel 50 are 65 held four arms 52 53 58 58, having rings 51 integral therewith, rotatably supported on unthreaded portions of the rod, the middle rings 51 being in contact with ring 45. Two of these arms (denoted by 52 and 53) are pivotally connected each to the inner lower end of a pad or pad-support 54. The ring 51 of the arm 53 is provided with teeth 55 or the like, adapted to engage with similar teeth on the ring 48 to securely lock these parts together 70 when they are properly engaged for the purpose by suitably turning the wheel 50.

Whenever it is desired to adjust the arms about their support to adapt the pads to fit the back hair of a female patient, for example, 95 the wheel-nut 50 should be unscrewed sufficiently to permit the several rings to have the necessary movement lengthwise of the supporting-rod 47, whereby they are loosened or unlocked to permit sufficient rotation. 100 The wheel-nut is ordinarily kept loose enough so that the teeth at 55 may be disengaged by pressing the pads toward each other. These teeth are made fine to facilitate the turning of the ring pertaining to arm 53. The upper 105 two of the four arms above referred to are indicated by 58. At 57 these are pivotally connected each with a limb 59.

The construction provides for several adjustments of each pad either by the occupant 110 of the chair or by others. For example, the arm 53 being held by the hand against rotation the corresponding arm 59 can be rotated about 57 to change the inclination of the pad by moving its upper or outer part. An arm 115 58 being held in like manner the arm 53 can be rotated and the pad tilted by a suitable movement of its lower part, the upper part remaining nearly stationary. Thus if it be desired to change the inclination of the pad without materially changing the elevation of its upper end, then an arm—as 53, for example—can be manipulated and the link 59 left undisturbed or held by the hand if necessary, or if 53 be held and 59 suitably manipulated 120 the inclination of the pad can be changed without materially changing the elevation of its lower end. Arms 52 and link 59 can be manipulated in like manner, the links 59 being suitably moved in each case. If in any 125 case the manipulation of the arms does not bind them together sufficiently to maintain

- their position by the operation of the inclined surfaces of the arm-rings, (indicated in Figs. 9 and 10,) then the parts can be tightened by the wheel-nut.
- 5 Obviously mere mechanical changes can be made in the several devices described herein without materially affecting their principles of construction and operation, and I do not wish to be limited to the use of the T-lever or of a particular number of tubes or of anti-friction devices or to other details except as pointed out.
- Having described my invention, what I claim is—
- 15 1. The combination of the pedestal, the tube 11 having a flattened exterior surface to provide a bearing for two laterally-adjacent series of balls, and the pedestal extension-tube, said pedestal extension-tube having channels 20 provided with antifriction-balls adapted to bear on the tube 11 and meditately on the pedestal, substantially as described.
2. The combination of the pedestal, the tube 11, and the pedestal extension-tube, said latter tube having channels provided with anti-friction-balls adapted to bear on said tube 11 and meditately on the pedestal, and with 25 adjustable bearing-plates for the balls intermediate the pedestal and its movable extension, substantially as described.
3. The combination of the pedestal, the tube 11, and the pedestal extension-tube, said latter tube having channels provided with anti-friction-balls adapted to bear on tube 11 and 30 meditately on the pedestal, and with adjustable bearing-plates for the balls intermediate the pedestal and its movable extension, one of the plates being made wide to furnish a bearing for two laterally-adjacent series of 35 balls, substantially as described.
4. The combination of the pedestal provided with interior tracks for antifriction devices, the seat-tube 11 supporting the chair-seat, the pedestal extension-tube intermediate 45 the pedestal and seat-tube, antifriction-balls carried by said pedestal extension, said balls situated near the top and bottom of the extension-tube being oppositely situated and bearing respectively on tube 11 and on the 50 pedestal-tracks, and the oil-reservoir situated in the path of the extension-tube, substantially as described.
5. In a dental chair, the combination of tubes to hold a liquid column for the raising 55 and lowering of a seat, a pump to force liquid into said tubes, a lever having a fulcrum supported by the pedestal and connected to the pump-piston, a lever having a fulcrum in the pedestal-wall with one arm extended 60 outside thereof and provided with an operating-crank, the other arm of said lever being situated within the pedestal and slotted, a lever having a fulcrum in the pedestal-wall below and adjacent the slotted lever and provided 65 with a pin situated in the slot of said slotted lever the arm of said lever with a pin being extended below its pin and loosely con-
- nected to the first-named lever, substantially as described.
6. In a dental chair, a supplemental seat-frame pivoted to the main seat-frame and adapted to support a supplemental seat above the main seat or to fold down within the foot-rest frame, substantially as described.
7. In a dental chair, a supplemental seat-frame pivoted to the main seat-frame and adapted to support a supplemental seat above the main seat or to fold down within the foot-rest frame, and a supplemental foot-rest pivoted to the supplemental seat-frame, substantially as described.
8. In a dental chair, a supplemental seat-frame pivoted to the main seat-frame and adapted to support a supplemental seat above the main seat or to fold down within the foot-rest frame, a supplemental foot-rest pivoted to the supplemental seat-frame, said supplemental foot-rest being adapted to be folded when the supplemental seat-frame is turned down and between the two frames, substantially as described.
9. A dental chair having a main seat-frame and a supplemental seat-frame, a detachable arm-rest, said rest and frames being provided with means whereby the rest may be connected to either seat-frame, substantially as described.
10. In a head-rest support, the ball of the ball-and-socket joint provided with an arm and ring the latter having an angular opening, the rod provided with an angular part intermediate its ends to movably fit the said angular opening, pad-supports having rings embracing said rod, and means for locking said rings together, the ball-arm ring being situated between said locking-rings, substantially as described.
11. In a head-rest the head-supporting pads provided with several arms movably held on a rod and the arm extending from the ball of a ball-and-socket joint, said rod and arm being rigidly connected circumferentially and loosely connected lengthwise the rod at a point near its center and means for fastening the arms together, substantially as described.
12. In a dental chair, the combination of the approximately cylindrical pedestal provided with a lateral enlargement 24" having relatively long and short sides 24" and 24", one side being approximately tangential 120 to the main body of the pedestal-wall, the pumps situated partly in the recess formed in the enlargement and adjacent said latter side, and the two-armed lever having a fulcrum in said side and movable parallel therewith, substantially as described.
13. The combination of telescoping tubes and means for moving a tube or tubes by fluid-pressure to extend them with a device for displacing a part of the fluid in the larger tube 130 or tubes, substantially as described.
14. The combination of telescoping tubes and means for moving a tube or tubes by fluid-pressure to extend them with a device for dis-

placing a part of the fluid in a larger tube or tubes, said device being attached to and movable with a tube, substantially as described.

15. The combination with telescoping tubes and means for moving a tube or tubes by fluid-pressure to extend them of a fluid-displacing plunger situated in the larger tube, said means for producing the pressure comprising one or more pumps and a compound lever to operate the same, substantially as described.

16. In combination the base having a flange 3' constituting with said base an oil-reservoir and having integral with its bottom an annular closed seat 13', the casting 13 rotatable in said seat and having pump-ports, a pump and tube 8 supported in said casting and the latter having an extension fixed to the pedestal whereby the casting supports the tube and pumps and moves with the pedestal, substantially as described.

17. The compound lever having a pivoted member 29, and a pivoted member 26, said members being loosely connected and each

provided with a separate pivot or fulcrum, and a lever 23 having a fulcrum 24 and loosely 25 connected to the lever 26 intermediate said levers 23 and 29, substantially as described.

18. In combination with a separable casting having an opening in its bottom and interior conduits, with inlet and outlet valve seats for 30 a pump-cylinder, one of said seats being immediately over the said opening, an upwardly-closing valve provided with a stem and a removable plug having a larger diameter than the valve situated in the bottom of the casting 35 immediately below the valve, said plug having a socket with closed bottom to receive the end of the valve-stem, substantially as described.

In testimony whereof I have signed this 40 specification in the presence of two subscribing witnesses.

MONT C. MERKER.
